UNITED STATES PATENT OFFICE.

FRIEND A. RUSS, OF GREENWICH, AND JOHN B. RUSS, OF DERBY, CONNECTICUT; SAID JOHN B. RUSS ASSIGNEE, BY MESNE ASSIGNMENTS, TO CHARLES H. WRIGHT, OF NEWARK, NEW JERSEY.

SUSPENDER-BUCKLE.

No. 893,263.

Specification of Letters Patent.

Patented July 14, 1908.

Application filed May 26, 1907. Serial No. 376,222.

To all whom it may concern:

Be it known that we, FRIEND A. Russ, residing in Greenwich, in the county of Fairfield and State of Connecticut, and 5 JOHN B. Russ, residing at Derby, in the county of New Haven and State of Connecticut, both citizens of the United States, have invented a new and useful Improvement in Suspender-Buckles, of which the following 10 is a specification.

Our invention relates to buckles, and more particularly to that class of the same which are used on running webbing.

One of the objects of our invention is to 15 provide a device of this character wherein the web is attached to the buckle without resorting to the expedient of sewing or stitching, and which is capable of being strung in such a manner that the same is 20 interposed between the buckle and garments to prevent any dampness or moisture in the latter from coming into contact with the buckle, thereby producing what is known in the trade as a rustless buckle.

25 Another object of our invention is to produce a buckle of such a configuration that only a relatively small amount of metal is required, a minimum amount of scrap produced, and which can be made out of two 30 pieces of metal in a minimum number of operations.

With these and other objects in view, our invention consists in details of construction and manner of operation more fully described in the following description and accompanying drawings in which like reference characters refer to corresponding parts.

In the drawings: Figure 1 is a front view of the buckle showing a part of the web-locking lever, and portions of the web broken away; Fig. 2 a longitudinal section taken on line $z-z$ of Fig. 1; Fig. 3 a similar view to Fig. 2 but showing the web-locking lever in its unclamped or open position; Fig. 4 a 45 view of the blank from which the frame is made; Fig. 5 a bottom plan view of the web-locking lever taken on line y of Fig. 2; Fig. 6 a view of the blank shown in Fig. 4, but showing an additional means for clenching the webbing; and Fig. 7 is a central vertical section of the buckle without the webbing and showing the web confining lip in its open condition.

The buckle generally comprises a back 5 frame A and a web-locking lever B. The

frame A may be made from a blank like that shown in Fig. 4 and consists of the sheet metal back plate a having the forwardly turned side ears b , b , perforated at c , c . The web-locking lever B is made out of a single 60 piece of sheet metal, and bent to form a shield g and an apron d the latter having preferably a serrated or toothed edge e and the integral projecting trunnions f , f which latter are journaled in the perforations c , c , of the 65 side ears b , b respectively. The front portion or shield of the lever is swelled outwardly and has its lower edge h turned slightly inwardly. The lower portion of the back plate a is bent or struck up rearwardly entirely across the plate forming the depressed portion i , and the lower edge j is turned forwardly and slightly upward as clearly shown at Fig. 7, in order that it may be forced down into the position shown at Figs. 2 and 3, to 70 clench and conceal the extremity of a webbing C. As will be clearly seen by reference to Figs. 2 and 3, the presence of this depression i , co-operates with the lower edge j , of the lip on the back plate to produce a crimp 75 in the webbing at the upper terminus of the depression, which serves to more securely hold the webbing against accidental release- 80 ment, and also enables the lip to be brought into alinement with the webbing. The lower 85 edge j may be serrated, feathered or otherwise roughened to more securely clench the web, and if desired, teeth j' may be struck up from the back plate to pierce the extremity 90 of the webbing and clench the same down on the face of the plate behind the turned up edge j . One end k of the webbing C is compressed and confined between the lip j and the body of the back frame a and the webbing thus attached to the frame passes upwardly 95 and turns over the top edge of the same at l and then runs into a downward reach m returning upon itself through the cast off D runs upwardly between the back plate and the web-locking lever into an upper reach n . 100 The upper edge e of the lever B co-acts with the uppermost portion of the back plate a to lock, grip or clamp the running portion n of the webbing to the underlying portion there- 105 of before it runs over the top edge of the plate, and the lower edge h of the front shield g of the lever co-acts with the lower portion of the back plate a to draw and stretch the running portion of the webbing tightly over the 110 underlying portion disposed over the front

face of the back plate. By passing that portion of the webbing adjacent to its confined extremity over an edge of the frame as at *l* causes the webbing to be frictionally engaged by said edge and relieves the strain at the confined extremity, thereby assisting in securing the webbing to the buckle.

The attaching of the extremity of the webbing to the lower portion of the front of the back plate and the drawing of the same over the top edge thereof firmly secures the same to the buckle and causes the lower edge of the frame *A* to swing forwardly free from the downward reach *m* out of the vertical plane of the latter over the bottom edge *h* of the front shield *g* of the lever *B*.

When the lever is locked and the webbing is under tension the latter is drawn or stretched tightly from its extremity over the front of the plate *a* thereby presenting a frictional surface substantially flush with the turned up lower portion *j* clenching the webbing into the depressed portion *i*. The running portion *n* of the webbing when clamped by the upper edge *e* of the apron *d* of the lever *B* draws upwardly on the edge portion *e* thereby causing the lower edge *h* of the shield *g* due to the lever acting as a bell crank, to draw the running webbing rearwardly over the bottom edge of the back plate stretching the webbing over the flat frictional underlying surface heretofore mentioned. The running webbing thus disposed over the back plate and engaged by the upper and lower edges of the lever is securely locked by these three parts and the strain and tension on the webbing distributed from the one part to the others until equilibrium is established thereby producing a well balanced device.

When the lever is unlocked as shown in Fig. 3 the back plate being substantially flush gives a free passage to the running portion of the webbing between the same and the parallel surface of the top of the apron *d*. Clenching the extremity of the webbing to the lower front portion of the back plate *a* dispenses with the necessity of forming a loop around the back plate and sewing the same together beneath the lower edge thereof the latter operation being much slower and more costly than clenching, and further the back plate being relatively narrow between its top and bottom edges permits a further economy in the length of the webbing, and the clenching and concealing of the extremity of the webbing constitutes a selvage and prevents any raveling thereof. The running portion of the webbing being locked against the underlying rearward portion along the uppermost portion of the back plate brings the upper and lower reaches *n*, *m* into parallel planes immediately adjacent to each other thereby presenting a substantially flat surface over the rear of the buckle

and between the same and the garments. The clenching of the extremity of the webbing to the front of the back plate also enables this plate to swing clear of the lower reach *m* thus permitting the same to run in a vertical plane instead of being drawn forwardly with the lower edge of the plate which would be the result should the webbing be looped around the plate and sewed.

While we have found our improved buckle as especially advantageous for use in connection with suspenders and have therefore fully illustrated and described such use, it will be obvious that it may be employed for other uses to which it may be applicable.

Having now described our invention what we claim and desire to protect by Letters Patent is:

1. As a new article of manufacture, a buckle provided with means for locking the running portion of a webbing and having a depression in the lower portion of the back plate adapted to receive the extremity of a webbing, and a projecting foldable lip for confining and concealing the end of such webbing, substantially as hereinbefore set forth.

2. The combination with a buckle for running webbing comprising a back plate and an angular lever journaled across the front thereof, of a web having its running portion passing between said plate and lever, and its extremity clenched to the front of said plate in the rear of said running portion and passed over the top edge of said plate into a downward reach, the said lever being mounted to have its upper edge co-act with the uppermost portion of said plate to lock the running portion of the web, and the lower edge of said plate being free to swing forwardly above the lower edge of said lever to draw the running portion of the web into frictional engagement with the extremity thereof passing over the front of the plate.

3. The combination with a webbing of a buckle for running webbing, comprising a sheet metal frame and a web locking lever journaled across the front thereof, the lower portion of said frame having an integral transversely disposed upturned web-gripping lip at the lower extremity thereof, the said lip being adapted to be pressed toward the body of said frame to grip the extremity of said webbing, said frame having a substantially straight edge around which the attached end of the webbing is drawn.

4. A buckle for webbing comprising a sheet metal back plate having its lower portion projecting therefrom in the form of an integral lip adapted to be folded towards the body of said plate to confine and conceal the extremity of such webbing, combined with a web-locking lever, having a shield and a web-locking edge, the said shield having its lower portion terminating below the lower extremi-

ity of said back plate when the lever is in its operative position.

5. A buckle for a webbing comprising a sheet metal back plate having forwardly turned side ears, the lower portion of said plate below said ears projecting therefrom in the form of an integral lip adapted to be folded towards said plate so that its extremity will be embraced between said ears to confine 10 and conceal the extremity of such webbing, combined with a web-locking lever mounted between said ears, the clamping edge of which when in its operative position will lie adjacent to the upper edge of said back plate.

15. 6. A buckle for a webbing comprising a sheet metal back plate having forwardly turned side ears, the lower portion of said plate below said ears projecting therefrom in the form of an integral lip adapted to be folded 20 towards said plate so that its extremity will be embraced between said ears to confine and conceal the extremity of such webbing, combined with web-locking means arranged to operate between said ears.

25. 7. The combination with a buckle comprising a sheet metal back plate and a web-locking lever journaled across the front thereof, of running webbing strung to embrace the front and rear faces of said plate, 30 the lower portion of the latter being bent forwardly and upwardly and pressed toward the body of said plate to confine and conceal the extremity of the webbing.

35. 8. The combination with a webbing, of a buckle comprising a sheet metal back plate and a web-locking lever journaled across the front thereof, the lower portion of said plate being bent forwardly and upwardly and pressed toward the body to confine and con-

ceal the extremity of the webbing, and the 40 said webbing being strung from said extremity to embrace the upper edge of said plate, but leaving the lower edge thereof free to swing forwardly against the front running portion of the webbing. 45

9. A buckle combined with webbing secured thereto by turning over the lower edge of the buckle frame in the form of a lip and swaging the same down across the extremity of the webbing then passing the latter over 50 the top edge of the frame to form a substantially flat and frictional surface on the front thereof, the running portion of the webbing passing upwardly in front of said surface and means for securing said running portion in 55 locking engagement with the underlying webbing.

10. The combination with a webbing of a buckle for running webbing, comprising a sheet metal frame and web locking means at 60 the front thereof, the lower portion of said frame having an integral transversely disposed upturned web-gripping lip at the lower extremity thereof, the said lip being adapted to be pressed toward the body of said frame to 65 grip the extremity of said webbing, said frame having a substantially straight edge around which the attached end of the webbing is drawn.

In testimony whereof we have hereunto 70 set our hands this 23rd day of May, A. D. 1907.

FRIEND A. RUSS.
JOHN B. RUSS.
